UNITED STATES PATENT OFFICE

161,956

REFRIGERATED DISPLAY TRAY

Mary D. Newburger, San Mateo, Calif.

Application June 12, 1950, Serial No. 10,472

Term of patent 14 years

(Cl. D80—11)

To all whom it may concern:

Be it known that I, Mary Dean Newburger, a citizen of the United States, residing in the city and county of San Mateo, State of California, have invented a new, original, and ornamental Design for Refrigerated Display Tray, of which the following is a specification, reference being had to the accompanying drawings, forming a part thereof:

The figure is a perspective view of the refrigerated display tray.

I claim:

The ornamental design for refrigerated display tray, as shown.

MARY D. NEWBURGER.
